Charles E. Wiener
ATTORNEY.

UNITED STATES PATENT OFFICE

JULIUS C. LOWRY, OF DETROIT, MICHIGAN

DESIGN FOR A LIGHTING FIXTURE

Application filed April 2, 1931. Serial No. 39,332. Term of patent 7 years.

To all whom it may concern:

Be it known that I, JULIUS C. LOWRY, a citizen of the United States, residing at Detroit, in the county of Wayne and State of Michigan, have invented a new, original, and ornamental Design for a Lighting Fixture, of which the following is a specification, reference being had to the accompanying drawings, forming part thereof.

Fig. 1 is a front elevation of a lighting fixture embodying my invention.

Fig. 2 is a side elevation thereof.

I claim:

The ornamental design for a lighting fixture as shown.

JULIUS C. LOWRY.
